REPAIR CLAMP

William H. Johnson, New York, N. Y.

Application January 29, 1942, Serial No. 428,695

1 Claim. (Cl. 20—92)

This invention relates to repair clamps. It is particularly directed to a clamp for repairing doors, screens, sash, and the like articles.

An object of this invention is to provide a clamp having clamp elements to engage opposite surfaces of the door, screen, sash or other article to be repaired, and means to draw the clamp elements together, the clamp elements being provided with prongs or teeth adapted to draw together the split portions of the article to be repaired.

Another object of this invention is to provide in a clamp of the character described, ribs on one or more of the clamp elements to strengthen the same and add to the appearance thereof, and also to put a spring tension on the bolt which interconnects the clamp elements.

Yet a further object of this invention is to provide in a clamp of the character described, clamp elements having conical countersunk portions and a bolt interconnecting said clamp elements having a conical head adapted to be received in the countersunk portion of one of the clamp elements, and a conical nut received in the conical countersunk portion of the other clamp element.

Still another object of this invention is to provide a strong, durable and compact clamp of the character described, which shall be easy to apply, which shall be relatively inexpensive to manufacture, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown various possible illustrative embodiments of this invention,

Fig. 1 is a top plan view of a flush type clamp embodying the invention, applied to a board or a sliding door;

Fig. 2 is a cross-sectional view taken on line 2—2 of Fig. 1, showing both flush and ribbed type;

Fig. 3 is a bottom plan view of the clamp;

Fig. 4 is a view similar to Fig. 3, and illustrating a modified construction;

Fig. 5 is a cross-sectional view of part of one of the bolts;

Fig. 6 is a partial, end view of one of the clamp elements; and

Fig. 7 is an end view of one of the clamp ele-

ments, and illustrating a modified construction.

Referring now in detail to the drawing, 10 designates a board which may be part of a door, screen or sash frame which has a generally longitudinal split S, and 11 designates a clamp embodying the invention, applied to the board 10 for drawing together the parts of the board on opposite sides of the split S. The clamp 11 comprises clamp elements 12 and 13, disposed on opposite sides of the board 10, and interconnected by bolts 14. The clamp 11 may be used to repair the board 10 if it has a split S running through the board 10.

Member 12 comprises a substantially flat plate made of metal, having a central longitudinal portion 15, from which there extends a plurality of parallel spaced pairs of oppositely extending, aligned arms 16. Thus, one pair of arms is disposed at the upper end of the longitudinal portion 15. One pair of arms is located at the lower end of said longitudinal portion, and one pair of arms is disposed mediate the ends of the longitudinal portion 15.

Any suitable number of pairs of arms 16 may be provided. The ends of the arms may be curved, as at 17, as illustrated in the drawing. Each of the arms is formed with a substantially conical countersunk portion 18 formed with a central opening 19. Furthermore at the top and bottom edges of each arm 16, is a prong 20 disposed at right angles to the plane of member 12.

Member 13 is likewise made of sheet metal, and has substantially the same shape as member 12. It is formed with a central longitudinal portion 23 and spaced, parallel pairs of oppositely extending arms 24. The arms 24, as well as the longitudinal portion 23, however are pressed outwardly along the central portions thereof, forming longitudinal ribs 23a and transverse ribs 24a. As shown in the drawing, around the edges of ribs 23a, 24a, are flat portions 23b, 24b which contact one surface of the board.

At the ends of arms 24 are also conical countersunk portions 30 formed with central openings 31, similar, and symmetrically disposed with respect to the countersunk portions 18. At opposite sides of each of the arms 24, are also prongs 27 perpendicular to the plane of member 13.

It will be noted that the clamp members 12 and 13 are applied to opposite sides of the board 10, with both clamp members aligned with each other. They are so placed that the prongs 20, 27 on the arms 16, 24, which extend in one direction, are on one side of the split S, and the prongs on said arms extending in said opposite direction, are on the opposite side of said split. The board

10 is drilled with through openings 33 aligned with the openings 19 and 31 of clamp elements 12, 13, and at the ends of through openings 33, are countersunk recesses 35 and 36 to receive conical portions 18 and 30.

Bolts 14 pass through the bolt openings 33. The bolts 14 have conical heads 14a received within the countersunk portions 30 of member 13. Screwed to the shanks of the bolts are conical heads or nuts 40 received within the countersunk portions 18 of clamp element 12. The prongs serve to draw together the portions of the board 10 on opposite sides of the split S. The nut 40 may be formed with a kerf 41 so that either the nut or the bolt may be turned with a screw driver to tighten the bolt.

In Fig. 4 there is shown a clamp member 13a, similar to member 13, except that it only has two pairs of outwardly extending arms instead of three pairs, as shown in Fig. 3. Otherwise, the clamp element 13a is the same as clamp element 13.

It will now be noted that the ribs 23a, 24a strengthen clamp element 13 and add to the appearance thereof, and also provide resiliency which aids in keeping the bolts from coming out.

In Fig. 7 there is shown a modified construction in which the prongs 50 have vertical, outer edges 51 and inclined, inner edges 52 to aid in drawing together the parts of the member to be repaired which are on opposite sides of the split.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

A repair clamp for wooden doors, screens, sash or like articles, comprising two members identical with each other, each member being formed of a rigid central longitudinally extending straightaway portion, spaced parallel pairs of oppositely extending arms in the same plane as said central longitudinally extending straightaway portions and at approximately right angles to said straightaway portions, said arms being spaced away from each other a distance slightly more than the width of the arms, and openings in the ends of the arms through which bolts may pass when the two members are aligned with each other on opposite sides of said wooden door, screen, sash or like article, to firmly secure the two members together.

WILLIAM H. JOHNSON.
